UNITED STATES PATENT OFFICE.

ANDREW J. COMPTON, OF TRENTON, NEW JERSEY.

CONCRETE POST AND SIMILAR STRUCTURE.

1,111,646.

Specification of Letters Patent. Patented Sept. 22, 1914.

Application filed August 15, 1913. Serial No. 784,979.

To all whom it may concern:

Be it known that I, ANDREW J. COMPTON, a citizen of the United States, residing at Trenton, in the county of Mercer and State 5 of New Jersey, have invented new and useful Improvements in Concrete Posts and Similar Structures, of which the following is a specification.

This invention relates to improvements in 10 concrete structures and especially with reference to the provision of a novel reinforcing element adapted to be embedded in a concrete structure as hereinafter more fully described and claimed.

15 In the accompanying drawings: Figure 1 is a vertical sectional view of a reinforced concrete post constructed in accordance with my invention. Fig. 2 is a transverse sectional view of the same. Fig. 3 is a detail 20 elevation of the reinforcing bar. Fig. 4 is a detail transverse sectional view of said reinforcing bar.

Referring first to the form of my invention shown in Fig. 1 the post 1, which is 25 made of concrete, is formed in a suitable mold and is provided with a reinforcing bar 2 which is embedded in the center thereof and is made of steel or iron. This bar comprises radially arranged webs 3, three 30 of such webs being preferably provided and each web is composed of a series of wings 4 the outer edges of which are curved so that the said wings are substantially scallop shaped or semi-circular in form and the said 35 wings are arranged at a slight angle to the axis of the bar so that their contiguous ends are out of line with each other and hence the wings by reason of such slightly oblique arrangement cause keys to be formed in the 40 concrete of which the post is composed and

hence the concrete of the post becomes securely fastened at all points throughout the length of the reinforcing bar to the angularly related webs of the latter and all longitudinal stresses on the post, as well as 45 transverse stresses are communicated directly to the reinforcing bar and hence the latter is efficient to thoroughly reinforce the posts under all conditions. The wings of 50 each series are arranged in overlapping relation to those of the adjacent series as shown. This reinforcing bar may also be embedded in curbing or in other concrete structures of similar character to reinforce the same. 55

I claim:

1. A concrete structure having a reinforcing element provided with webs composed of semi-circular wings arranged obliquely to the axis of said reinforcing element and with 60 their contiguous ends arranged out of line with each other whereby spaces are formed between adjacent offsets to form bonding recesses for the concrete.

2. A concrete structure having a reinforcing element provided with webs composed of wings arranged obliquely to the axis of said reinforcing element and with their contiguous ends out of line with each other whereby spaces are formed between adjacent 70 offsets to form bonding recesses for the concrete, the said webs being angularly related with reference to one another. 65

In testimony whereof I affix my signature in presence of two witnesses.

ANDREW J. COMPTON.

Witnesses:

WALTER F. SMITH,
J. C. STRICKER.
